UNITED STATES PATENT OFFICE

2,202,034

WELL HEATER

William K. Thomas, La Porte, Tex.

Application June 1, 1937, Serial No. 145,739

6 Claims. (Cl. 219—33)

This invention relates in general to well heating devices, and more particularly has reference to a heater adapted to be lowered into a well or the like for the purpose of heating the same and assisting in the removal of foreign deposits on the walls thereof.

Particularly in connection with oil wells there is formed after a period of time a deposit of paraffine or the like on the walls of the well and on the screen or strainer at the bottom of the wall where such a structure is employed. This deposit of paraffine sooner or later becomes such as to obstruct the flow of the well and prevent it from producing the amount of fluid which it would otherwise be capable of producing.

It is an object of this invention to provide a device for supplying heat at a desired point or points within the well for the purpose of melting or softening the paraffine or other deposits and make possible their removal.

It is a further object of this invention to provide an improved heating device of the type set forth in which electrical heating elements will be employed and although protected in the greatest possible degree from damage by contact with foreign objects and from contact with the fluid in the well, will be enabled to supply the maximum amount of heat to the well without themselves becoming overheated.

It is a further object of this invention to provide a heater of the type set forth in which the various heating elements may be removed and replaced with relative ease.

It is a further object of this invention to combine a device for supplying heat to the well with a means for mechanically removing the deposits therefrom either before or after the same has been heated.

Other objects and advantages of this invention will become apparent from the following description taken in connection with the accompanying drawing, the same being by way of illustration and example, however, and not by way of limitation. This invention is to be limited only by the prior art and by the scope of the appended claims.

Referring now more in detail to the drawing,

Fig. 1 is a vertical cross section through a portion of a well showing in elevation therein a heater constructed in accordance with this invention.

Fig. 2 is a view partly in vertical cross section showing the details of the heater illustrated in Fig. 1.

Fig. 3 is an elevation of one of the heating elements of the heater shown in Figs. 1 and 2.

Fig. 4 is a horizontal cross section taken along the line 4—4 of Fig. 2.

Fig. 5 is a similar view taken along the line 5—5 of Fig. 2.

Fig. 6 is a view similar to Fig. 2 but illustrating a modified form of heater.

Fig. 7 is a view similar to Fig. 4 and Fig. 5 but taken along the line 7—7 of Fig. 6.

In Fig. 1 there is illustrated a section of a well casing 1 having a strainer or screen 2 adjacent the lower end thereof. Within this casing 1 there is suspended by means of a tubing 3 or the like a heater constructed in accordance with this invention. To the collar 4 which is secured to the lower end of the tubing 3 there is threadedly engaged the upper tubular extension 5 of an elongated body 6 which is preferably constructed of cast iron or some similar material forming a relatively good conductor of heat. Communicating with the tubular section 5 is an opening 7 which extends the entire length of the elongated body member 6, thus providing a passageway from the lower end of this body member upwardly into the tubing 3. At intervals along its length the body member 6 is also provided with laterally extending openings 8 communicating with the passages through the interior of the body member 6 and opening to the exterior of this body member.

The body member 6 intermediate the lateral passageways 8 is provided with a plurality of elongated sockets or grooves each of which is adapted to receive an elongated bar 9 of cast iron or similar material within which is completely imbedded a U-shaped electric heater element 10 and a terminal 11 at the upper end thereof.

It may be stated at this point that the heater elements here employed may be purchased on the open market and that per se they form no part of this invention. They are provided with a highly heat conductive electrical insulation and in forming the elements 9 of cast iron these heater elements may be cast within the elements 45 themselves, thus forming an absolute protection against contact of the elements with any foreign objects which might damage them, and against contact with the liquid within the well. However, the cast iron or the like which surrounds 50 the elements is a highly heat conductive material, and the heat is thus readily conducted away from the elements themselves so that they are not permitted to become overheated as has been the case in previous constructions where in order 55

to secure proper electrical insulation heat insulating means have been employed.

The elements 9 are placed in position within the sockets in the body 6 and their upper terminals 5 11 are connected with a cable or the like 12 which passes upwardly to the top of the well and is connected with a suitable source of electrical energy. Enclosing and forming a chamber about the upper ends of the elements 9 and about the 10 connections 11 is a member 13 which might be termed a bonnet having its upper end 14 hollowed out to provide a stuffing box surrounding the tubular portion 5 of the body and having its lower end of substantially the same internal 15 diameter as the upper end of the body. Within the stuffing box 14 at the upper end of the bonnet 13 is a suitable packing 15 adapted to be compressed by means of a gland 16 so as to form a fluid-tight seal about the tubular portion 5 of 20 the body. A bushing 17 forms a seal about the cable 12 at the point where it passes through the bonnet 13 and upwardly to the surface of the well, and the space within the bonnet is adapted to be partially or completely filled with moulded 25 electrical insulation of any one of a number of well known types.

Secured to the lower end of the bonnet and extending downwardly about the body 6 and the elements carried thereby is a tubular member 30 19 forming a sheath about the body and having a coupling at its lower end for a purpose to be presently set forth. This member 19 has perforations 21 therethrough adapted to register with the openings 8 in the body of the heater 35 so that fluid may circulate up through the body and out these lateral openings, or vice versa.

Secured in the coupling 20 and extending downwardly therefrom is a short section of pipe 22 on the lower end of which are mounted one 40 or more up-turned packing cups 23, so that upon upward movement of the heater these packing cups will drag upwardly along the walls of the casing 1 and tend to remove therefrom any foreign accumulations.

45 Referring now to the modification illustrated in Figs. 6 and 7, this form illustrates a unitary heater in which the heating elements are not separately removable. In this construction, a body 24 is formed about one or more heating elements 25 in such a manner as to leave the central portion of the body free, this central portion of the body being formed with an opening 26. Adjacent the upper end of the openings 26 there are provided a plurality of lateral outlets 27 so 55 that fluid may circulate up through the body, through the passageway 26 and out through the openings 27.

Threadedly engaged with the upper end of 60 the body 24 is a bonnet 28 constructed in a manner similar to that illustrated in Fig. 2 and forming a closure about the connections 29 at the upper ends of the heater elements. A cable 30 passes from the connection 29 out through the 65 bushing 31 and upwardly into the top of the well, thus providing a means for transmitting energy to the heater element 24. The interior of this bonnet 28 is partially or wholly filled with a moulded electrical insulation 32 in much the 70 same manner as that described in connection with Fig. 2. It is noted that in this instance the insulation is shown as forming a closure at the upper end of the passage 26 through the body 24 so that circulation through the passage 26 will 75 necessarily pass through the lateral opening 27

and will not pass through or into the tubing above the heater element.

In view of the foregoing, it will be noted that a heater has been provided in the form illustrated in Fig. 2 in which the destruction of one or more of the heating elements will not necessitate a discarding of the heater, but that these elements may be removed and replaced singly so that the heater as a whole may go on in use. It is to be noted that the casting constituting the 10 body of the heater illustrated in Fig. 2 is a much more complicated and hence a much more expensive casting than the casting 9 in which the heating elements 10 are imbedded. Thus, the replacement of the casting 9 is much less expensive than would be the replacement of the entire heater if this were necessary upon the burning out of one of the heating elements. Furthermore, it is to be noted that the heating elements are surrounded with bodies which will positively 15 protect them against any outside destructive influence, including the fluid within which they operate, but that the protecting bodies are formed of a highly heat conductive material such that the heat will be conducted away from the 20 elements and the elements not allowed to become over-heated. In this connection, it is to be noted that while cast iron is mentioned as a material which may be used for the body of the heater, any other suitable material having the desired 25 characteristics of high heat conductivity and strength to protect the heating elements may be employed. This is also true of the form illustrated in Fig. 6.

In addition to the foregoing, it is to be noted 35 that the present invention makes possible the circulation of fluid through the heater and the carrying away of the heat therefrom so that the heating elements are even less likely to become over-heated.

Furthermore, the applicant has provided a combination of a heater for loosening the deposits upon the walls of a well casing with a means for positively and mechanically removing 40 these deposits.

It will thus be seen that a means has been provided for carrying out all the objects and advantages sought by this invention.

Having described my invention, I claim:

1. In a well heater, an elongated primary body of highly heat conductive material having longitudinal laterally open sockets therein, secondary bodies of highly heat conductive material removably positioned within said sockets, respectively, and of a size to substantially completely fill the same, and a U-shaped electrical heater element molded into each of said secondary bodies.

2. In a well heater, an elongated primary body of highly heat conductive material having longitudinal sockets therein, secondary bodies of highly heat conductive material removably positioned within said sockets, respectively, and of a size to substantially completely fill the same, a U-shaped electric heater element completely embedded in each of said secondary bodies, said primary body having an opening centrally thereof and extending from one end to the other and tubing connected to one end of said opening and extending upwardly from said body.

3. In a well heater, an elongated primary body of highly heat conductive material having longitudinal sockets therein and a central opening therethrough, secondary bodies of highly heat conductive material removably positioned within 75

- said sockets, respectively, and of a size to substantially completely fill the same, a U-shaped electric heater element completely embedded in each of said secondary bodies, and a sheath about 5 said primary and secondary bodies for retaining said secondary bodies in place in said socket, said primary body and said sheath having registering lateral openings communicating with the central opening through said primary body.
- 10 4. In a well heater, a metal body having a passageway centrally thereof and lateral openings into said passageway, said body having laterally open grooves extending along its outer sides, metal bodies snugly and removably fitting said 15 grooves, and insulated electrical heater element embedded in and snugly embraced by each of said last mentioned metal bodies, and means for securing said last mentioned metal bodies in place in said grooves.
- 20 5. In a well heater, a metal body having a passageway centrally thereof and lateral openings into said passageway, said body having laterally open grooves extending along its outer sides,

metal bodies snugly and removably fitting said grooves, and insulated electrical heater element embedded in and snugly embraced by each of said last mentioned metal bodies, and means for securing said last mentioned metal bodies in 5 place in said grooves, said lateral openings through said first body being disposed between said grooves.

6. In a well heater, an elongated body of highly heat conductive material having longitudinal 10 sockets therein which sockets are open laterally with respect to said body throughout substantially their entire length and width, a secondary body of highly heat conductive material removably positioned within and substantially completely filling each of said sockets respectively, each of said secondary bodies being removable in a lateral direction with respect to said elongated body and through the said lateral openings from said sockets, and an electrical heater ele- 15 20 ment molded into each of said secondary bodies.

WILLIAM K. THOMAS.
